UNITED STATES PATENT OFFICE.

JAMES CAVANAGH, OF DORCHESTER, AND LAURENCE E. TOPHAM, OF SWAMPSCOTT,
MASSACHUSETTS, ASSIGNEES TO UNITED SHOE MACHINERY CORPORATION, OF
PATERSON, NEW JERSEY, A CORPORATION OF NEW JERSEY.

SHOE-SUPPORTING JACK.

Application filed February 5, 1920. Serial No. 356,585.

To all whom it may concern:

Be it known that we, JAMES CAVANAGH and LAURENCE E. TOPHAM, citizens of the United States, residing, respectively, at Dorchester, in the county of Suffolk, and Swampscott, in the county of Essex, State of Massachusetts, have invented certain new and useful Improvement in Shoe-Supporting Jacks; and we do hereby declare the following to be a full, clear, and exact description of the invention, such as will enable others skilled in the art to which it appertains to make and use the same.

This invention relates to shoe supporting jacks, and more particularly, to jacks of the class which are adapted to be employed to support the shoe in machines for inserting a continuous line of fastenings through an upper and an insole or a turn shoe sole to attach the same securely and permanently together.

The primary object of the invention is to provide an attachment for jacks of the above class which will enable certain parts of the upper to be secured properly to the sole without lasting these parts and securing the same in position by temporary fastenings.

With the above object in view the present invention comprises one or more devices for engaging the upper and causing the same to conform to the last operating to hold the upper in position during the attaching operation. In the preferred form of the invention, the upper engaging devices are mounted for movement toward and from the lasted shoe to carry the same into and out of operative position. This enables these devices to be located so that they will not obstruct the placing of a shoe on the jack or the removal of a shoe therefrom. In the particular form of the invention illustrated in the present application, these devices consist of pivoted arms arranged to engage the upper along the shank at the opposite sides of the shoe and wipe the upper over the last so as to enable the upper along these parts of the shoe to be secured to the insole without the usual side lasting operation.

As illustrated in the present application, the invention is applied to a jack of the

type the parts of which are arranged so that upon placing the shoe on the jack the shoe is automatically adjusted in a predetermined position with relation to the jack and clamped in adjusted position, and that upon the turning of the jack back to starting position after the completion of the attaching operation the parts of the jack are actuated to unclamp the shoe and restore the jack to its initial condition. In this construction the upper engaging devices are swung inwardly toward the shoe as the shoe is adjusted and clamped on the jack, and are swung outwardly away from the shoe as the parts of the jack are restored to their initial condition.

The various features of the invention will be readily understood from the accompanying drawings illustrating the invention in its preferred form and the following detailed description of the constructions therein shown.

In the drawings Figure 1 is a view partly in front elevation and partly in section of the jack; Fig. 2 is a view similar to Fig. 1 illustrating the parts in different positions; and Fig. 3 is a detail view illustrating particularly the upper engaging devices.

With the exception of the upper engaging devices and the mechanism for actuating and controlling the same, the parts of the jack illustrated in the drawing have the same construction, arrangement and mode of operation as the corresponding parts of the jack illustrated and described in the pending application of Laurence E. Topham, Serial No. 269,076, filed December 31, 1918. To enable the invention to be better understood, however, the jack will be rather briefly described in the present application.

The jack comprises a heel support 2 and a toe rest 4 mounted upon a spindle 6. The jack is preferably supported in the machine in the same manner as the jack of the above Topham application, so that longitudinal and lateral tipping movements and lateral turning movements may be imparted to the jack to present the various parts of the shoe to the fastener inserting mechanism. As illustrated and described in said applica-

tion, the supporting devices for the jack are connected with the lower end of the jack spindle and are constructed and arranged so that the spindle is freely rotatable and is 5 free to tip in any direction about its lower end, and that the lower end thereof is free to move in any horizontal direction.

As stated above, the jack of the present application is constructed and arranged so 10 that upon the placing of the shoe on the jack the shoe is automatically located in a pre-determined and unvarying position lengthwise of the jack regardless of the size of the shoe placed on the jack and is securely 15 clamped in adjusted position, and that, at the completion of the operation on the shoe, the shoe is unclamped and the parts of the jack are restored to their initial positions 20 ready for the application of another shoe to the jack. The jack comprises an arm 8 rigidly secured to the spindle upon the upper end of which the toe rest 4 is mounted, an arm 10 pivoted at 12 to the central portion 25 of the jack-frame, and a lever 14 pivoted at 16 on the arm 10 and having the heel support 2, consisting of a last pin, mounted thereon. The arm 10 is acted upon by a coiled spring 18 which tends to swing the same toward the arm 8. This spring is 30 connected with a pin 20 mounted in a lever 22 and having its ends engaged in slots 24 in the arm 10. The lever 22 is pivoted at 26 on the arm 10, and is connected with the lever 14 through intermeshing gear teeth. 35 The spring 18 thus, under certain conditions, tends to swing the lever 14 in a direction to depress the toe of the shoe.

Before a shoe is placed on the jack preparatory to starting an operation, the arm 40 10 is held in a position relatively remote from the arm 8 against the tension of the spring 18, as shown in Fig. 1. The mechanism for holding the arm in this position comprises a lever 28 pivoted at 30 on the 45 jack-frame, a toggle 32-34 connecting the lever 28 with the arm 10, a lever 36 also pivoted at 30 and carrying an abutment screw arranged to engage the lever 28, a bevel gear 38 meshing with a gear segment 50 40 formed on the lever 36 and a shaft 42 to which the gear 38 is secured, passing centrally through the spindle 6. Devices are connected with the lower end of the shaft 42 which hold the shaft from turning movement while permitting the shaft to tip in 55 any direction with the jack spindle.

The toggle 32-34 before a shoe is placed on the jack is in a straightened condition as shown in Fig. 1, thereby holding the arm 60 10 in position against the action of the spring 18. Upon the placing of the shoe on the jack the toggle is broken by the depressing movement imparted to a vertically movable pin 44 engaged by the last which 65 operates through certain connections to

swing the outward member of the toggle upwardly. These connections comprise a pivoted dog 46 mounted on a block secured to the lower end of the pin 44 and arranged to engage a lateral projection on an arm 48 secured to the member 34 of the toggle. The pin 44 is depressed by the engagement of the last therewith as the last pin is seated in the last pin hole. The breaking of the toggle allows the spring 18 to act to swing the arm 70 10 toward the arm 8.

The swinging movement of the arm 10 brings the toe of the shoe into engagement with the upper face of the toe rest, which is inclined so that the toe of the shoe is lifted 80 as it slides along this surface, thereby swinging the levers 14 and 22 relatively to the arm 10 and bringing the spring 18 into action on said levers. Thus when the shoe is finally located on the jack and the swinging movement of the arm 10 ceases, the spring 18 acts to maintain the shoe in adjusted position longitudinally of the jack, and the tendency of the spring to tilt the lever 14 in a direction to depress the toe of 85 the shoe clamps the shoe firmly on the jack.

When the toe of the shoe reaches a pre-determined position with relation to the jack the swinging movement of the arm 10, under the action of the coiled spring 18, is positively arrested. The mechanism for stopping the swinging movement of the arm 10, comprises a bar 50 pivotally connected at one end with the arm and provided with rack teeth at its other end engaging a pinion 52 journaled in the arm 8 to which is secured a ratchet wheel 54. A pawl 56 is arranged to engage the ratchet wheel 54 and is controlled through a pivoted latch 58 and a rod 60 from a feeler lever 62 arranged to be engaged by the toe of the shoe. When the shoe is applied to the jack, the pawl 56 is held out of engagement with the ratchet wheel 54 by a projection on the bar 50. During the adjusting movement of the shoe the pawl is held out of engagement with the ratchet wheel by the latch 58, allowing the ratchet wheel to rotate freely. When the bulge in the toe portion of the upper 105 engages the feeler lever 62 the latch 58 is actuated to release the pawl and the pawl engages the ratchet wheel, thereby stopping the swinging movement of the arm 10.

During the turning movement imparted 110 to the jack in an operation on a shoe, the toggle 32-34 is straightened through the engagement of the gear segment 40 with the non-rotating gear 38. During the turning movement in the reverse direction imparted 115 to the jack in restoring the same to starting position after the completion of the operation, the toggle is actuated to swing the arm 10 back to the position shown in Fig. 1, thereby unclamping the shoe so that it is free 120 to be lifted from the jack.

The devices for engaging the upper and pressing the same down into position with relation to the marginal portion of the sole consist of arms 64 mounted on opposite sides of the jack and having inwardly curved outer ends arranged to engage the outside of the upper adjacent its margin, as shown in Fig. 3. To enable the arms 64 to swing toward and from the shoe, the arms are mounted respectively upon rotatable shafts 66 engaging in bearings carried respectively by the arms 10 and 8. Each of the upper engaging arms 64 is loosely mounted on the corresponding shaft 66 and is acted upon by a coiled spring 68 which tends to swing the arm inwardly relatively to the shaft. The movement of the arm under the influence of the spring, however, is limited by the engagement of the arm with a lateral projection 70 formed on a collar 72 secured to the shaft. With this construction, as the shafts 66 are turned in a direction to swing the arms 64 outwardly, the arms are swung with the shafts by the engagement of the projections 70 with the arms. As the shafts 66 are turned in the opposite direction to swing the upper engaging arms inwardly, said arms swing with the respective shafts until the ends 30 of the arms engage the upper, wipe the upper over the last, and force the same down firmly into position with relation to the marginal portion of the sole. During the further turning movement of the shafts the springs 68 allow the arms to yield with relation to the shafts, and the arms are held yieldingly against the upper.

Each of the shafts 66 is journaled at its left hand end in a block 73 pivoted by means of a stud 74 to the swinging arm 10, and the opposite end of the shaft is mounted to turn and slide longitudinally in a bearing in a sleeve 76 pivoted by means of a stud 78 to the arm 8.

With this construction the right hand end of each of the shafts 66 slides through the corresponding sleeve 76 as the arm 10 is swung toward and from the arm 8, as will be clear from an inspection of Figs. 1 and 2. When the arm 10 is located in the position shown in Fig. 1, the upper engaging arms 64 are located in their outer positions, as shown in dot and dash lines in Fig. 3. As the arm 10 is swung toward the arm 8 to adjust and clamp the shoe, the shafts 66 are turned to swing the upper engaging arms 64 into their inner positions, as shown in full lines in Fig. 3. As the arm 10 is swung back to the position shown in Fig. 1 to unclamp the shoe, the shafts 66 are rotated to swing the upper engaging arms 64 back to their outer positions. Each of the shafts 66 is rotated in the manner described by the engagement of a roll 80 mounted

on the stud 78 with a contact surface 82 formed on the shaft.

The outer and inner portions of each of the contact surfaces 82 are formed at an angle to each other, and the intermediate portion of said surface has a twist or spiral 70 form so that each of the shafts is turned in its bearings by the cooperative action of the roll 80 and the contact surface 82 as the shaft is moved longitudinally through the sleeve 76. The contact surfaces 82 on the two shafts are so constructed that as the arm 10 is swung toward the arm 8 to adjust and clamp the shoe, the movement of the shafts through the sleeves 76 will cause the shafts to be turned in a direction to 80 carry to upper engaging arms 64 inwardly into engagement with the upper, and that as the arm 10 is swung back away from the arm 8 to unclamp the shoe the movement of the shafts through said sleeves will cause 85 the shafts to be turned in the opposite direction to swing the upper engaging arms outwardly to their initial positions. Thus when the parts of the jack are in position to receive the shoe the upper engaging devices are widely separated so as not to obstruct the placing of the shoe on the jack. As the shoe is adjusted and clamped on the jack, these devices are swung inwardly into upper holding positions and as the shoe is 95 unclamped and the parts of the jack are restored to their initial positions, said devices are swung outwardly so as not to obstruct the removal of the shoe from the jack.

The upper engaging arms 64 are preferably each constructed in two parts, as shown clearly in Figs. 2 and 3, the outer part of each of said arms being secured to the inner part thereof by screws 84 passing 105 through slots 86 in said outer part and threaded into the inner part. This enables the outer part of each arm to be adjusted relatively to the inner part to vary the length of the arm.

As illustrated in the drawing, the upper engaging arms are especially constructed for use in sewing the inseams of welted and turned shoes, and are arranged to engage the upper along the shank of the shoe upon opposite sides thereof so as to hold the upper in position to be sewn to the sole without any preliminary side lasting. These arms are located so as to hold the upper in position close to the marginal portion 120 of the sole without interfering with the needle or with the other parts of the inseam sewing mechanism and therefore may be maintained in operating position during the entire sewing operation. Fig. 3 shows the 125 positions in which the needle and the welt guide operate with relation to the upper engaging arms, these parts being shown in

dot and dash lines in this figure and being indicated by reference numerals 88 and 90 respectively.

Having explained the nature and object 5 of the invention, and having specifically described a mechanism embodying the invention in its preferred form, what is claimed is:

1. A shoe supporting jack having, in combination, a support for a lasted shoe, one or more devices for engaging the upper and causing the same to conform to the last, operating to hold the upper in position to be attached to a ribbed sole during the formation of a line of fastenings through the upper and rib in a plane parallel to the sole surface, means for supporting said devices for movement into and out of operating positions, and automatically acting mechanism for actuating said devices.

2. A shoe supporting jack having, in combination, a support for a lasted shoe, mechanism for clamping the shoe on the jack, one or more devices for engaging the upper at the sides of the last and causing the upper to conform to the last, and mechanism arranged to be actuated to move said devices into upper holding positions as the shoe is initially clamped on the jack.

3. A shoe supporting jack having, in combination, a support for a lasted shoe, mechanism for adjusting the shoe on the jack, one or more devices for engaging the upper and causing the same to conform to the last, and mechanism arranged to be actuated to move said devices into operating positions as the shoe is adjusted on the jack.

4. A shoe supporting jack having in combination, a support for a lasted shoe, mechanism for adjusting the shoe on the jack, mechanism for restoring the parts of the jack to their initial positions, one or more movable devices for engaging the upper and causing the same to conform to the last, and means arranged to be actuated to move said devices out of operating positions as the parts of the jack are restored to their initial positions.

5. A shoe supporting jack having, in combination, a support for a lasted shoe, a pivoted upper engaging arm for causing the upper to conform to the last, a shaft on which said arm is mounted to turn relatively to the shaft, a spring connecting the arm with the shaft to cause the arm to swing with the shaft as the shaft is turned in a direction to carry the arm toward the shoe and allowing the arm to yield relatively to the shaft after the arm engages the shoe, and an abutment carried by the shaft for engaging the arm to swing the arm away from the shoe as the shaft is turned in the opposite direction.

6. A jack for shoe machines having, in combination, a support for a lasted shoe, 65 a pivoted arm for engaging the upper and causing the same to conform to the last, a shaft upon which said arm is mounted, a cam face formed on the shaft, a roll engaging said cam face and cooperating therewith to turn the shaft to swing the arm toward and from the shoe as the roll and shaft are moved relatively in directions lengthwise of the shaft, and means for relatively moving the roll and shaft.

7. A jack for shoe machines having, in combination, two arms mounted for relative movement toward and from each other, a heel support mounted on one of said arms, a toe rest mounted on the other of said arms, a pivoted arm for engaging the upper and causing the same to conform to the last, and mechanism operating respectively during the relative movement of the first two arms toward and from each other to swing the upper engaging arm toward and from the shoe.

8. A shoe supporting jack mechanism having, in combination, a jack for supporting a lasted shoe, one or more devices for engaging the upper and holding it in position to be attached to the sole, and mechanism acting automatically when thrown into operation to jack a shoe placed on the jack and to move said devices into engagement with the upper.

9. A shoe supporting jack mechanism having, in combination, a jack for supporting a lasted shoe, one or more devices for engaging the upper and holding it in position to be attached to the sole, and mechanism acting automatically when thrown into operation to clamp the shoe on the jack and to move said devices into engagement with the upper.

10. A shoe supporting jack mechanism having, in combination, a jack for supporting a lasted shoe, one or more devices for engaging the upper and holding it in position to be attached to the sole, and mechanism acting automatically when thrown into operation to locate the shoe in a predetermined position longitudinally on the jack and to move said engaging devices into engagement with the upper.

11. A shoe supporting jack mechanism having, in combination, a jack for supporting a lasted shoe, one or more devices for engaging the upper and holding it in position to be attached to the sole, mechanism acting automatically when thrown into operation to jack a shoe placed on the jack and to move said engaging devices into engagement with the upper, and mechanism acting at the completion of an operation on the shoe to unjack the shoe, restore the parts of the jack to initial position and move

said engaging devices out of engagement with the upper.

12. A shoe supporting jack having, in combination, a toe rest and a heel support relatively movable to adjust the shoe on the jack, one or more devices for engaging the upper and holding it in position to

be attached to the sole, and means for moving said devices into engagement with the shoe during the relative movement of the toe rest and heel support in adjusting the shoe on the jack. 10
